COMBINED AQUARIUM AND LAMP BASE

Bob J. Hullender, P.O. Box 11068,
Santa Rosa, Calif. 95406

Filed July 10, 1972, Ser. No. 270,252

Term of patent 14 years

Int. Cl. D26—05

U.S. Cl. D48—20 D

FIG. 2.

FIG. 3.

FIG. 4.

FIG. 6.

FIG. 7.

FIG. 8.

FIG. 10.

FIG. 11.

FIG. 12.

FIG. 14.

FIG. 15.

FIG. 16.

FIG. 1 is a perspective view of a combined aquarium and lamp base showing my new design;

FIG. 2 is a top plan view thereof;

FIG. 3 is a sectional view taken along line 3-3 of FIG. 2;

FIG. 4 is a side elevational view thereof;

FIG. 5 is a perspective view of a second embodiment of the combined aquarium and lamp base of my new design;

FIG. 6 is a top plan view of the combined aquarium and lamp base shown in FIG. 5;

FIG. 7 is a sectional view taken along line 7-7 of FIG. 6;

FIG. 8 is a side elevational view of the combined aquarium and lamp base shown in FIG. 5;

FIG. 9 is a perspective view of a third embodiment of the combined aquarium and lamp base of my new design;

FIG. 10 is a top plan view of the combined aquarium and lamp base of FIG. 9;

FIG. 11 is a sectional view taken along line 11-11 of FIG. 10;

FIG. 12 is a side elevational view of the combined aquarium and lamp base of FIG. 9;

FIG. 13 is a perspective view of a fourth embodiment of the combined aquarium and lamp base of my new design;

FIG. 14 is a top plan view of the combined aquarium and lamp base shown in FIG. 13;

FIG. 15 is a sectional view taken along line 15-15 of FIG. 14; and

FIG. 16 is a side elevational view of the combined aquarium and lamp base shown in FIG. 13.

I claim:

The ornamental design for a combined aquarium and lamp base, as shown and described.
